TO LYMAN GUN SIGHT CORPORATION, OF MIDDLEFIELD, CONNECTICUT, A CORPORATION
OF CONNECTICUT.

SIGHT FOR FIREARMS.

No. 873,112.

Specification of Letters Patent.

Patented Dec. 10, 1907.

Application filed January 16, 1907. Serial No. 352,627.

To all whom it may concern:

Be it known that we, JAMES WINDRIDGE and GEORGE S. WILCOX, citizens of the United States, and residents of Middlefield, 5 in the county of Middlesex and State of Connecticut, have invented certain new and useful Improvements in Sights for Firearms, of which the following is a full, clear, and exact specification.

10 Our invention relates to a sight for firearms, and it has for its object to provide a leaf sight which shall embody a sight notch of variable form, or a series of sight notches of different forms which may individually be 15 brought into sighting position by ready adjustment of parts.

The invention consists in the novel combination with the leaf of a pair of adjustable sight blades shaped or adapted to form the 20 respective sides of the sighting notch, or having individual notches which may be set in sighting position by adjustment, and in the arrangement and construction of parts 25 as hereinafter more fully described and claimed.

In the accompanying drawings comprising a part of this specification, Figure 1 is a side elevation of one modification of a sight embodying our improvements, and which 30 forms the subject of a separate application. Fig. 2 is a rear elevation of the same. Fig. 3 is a side elevation of a sight embodying our improvements in the form which specifically comprises the subject of this application. 35 Fig. 4 is a rear elevation of the same. Figs. 5, 6 and 7 are elevations similar to Fig. 4, respectively showing different arrangements and combinations of the sighting blades and sight notches. Fig. 8 is a vertical cross section on the line $x-x$ Fig. 5. Fig. 9 is a vertical lengthwise section on the line $x-x$ Fig. 8. Figs. 10 and 11 are views of the sight blades removed from the leaf. Fig. 12 is a rear elevation of a leaf sight and its sight blades embodying different forms of notches from 40 those shown in the preceding figures. Fig. 45 13 a similar view of the sight illustrated in Fig. 12 with the notches arranged to form a different shape of sighting notch.

50 In the above description of the figures the terms side and rear elevation, cross and lengthwise section relate to the position of the sight when mounted on a firearm, instead of to the actual proportions of the

sight, which in fact has its longest dimension 55 in operation extended crosswise of the gun barrel.

Referring to the drawings, A, designates a sight base of a common and well known form having beveled front and rear edges, b, 60 adapted to be inserted in a transverse dovetailed notch on the upper side of the barrel of a firearm. The configuration of the upper surface of the base is such that a hinge ear, d, is provided at each end thereof, in the central vertical plane between the beveled edges, b. The perforations, e, through the ears are in alignment with each other and screw threaded to receive the screw studs, f, which are inserted from the outer sides of the ears 70 and are provided with the reduced cylindrical portions, g, projecting inwardly from the ears or toward each other, as shown in Fig. 9. The said cylindrical portions, g, comprise the pivots upon which the folding 75 leaf or sight carrying part is hinged. It is common in this class of sights to mount a pair of leaves upon the same axis, in which case, as in the drawing, the main leaf, h, may be provided with a pair of eyes, i, fitting between the hinge ears, d, and the secondary leaf, L, formed with a single eye, m, fitted between those of the main leaf.

It is to the main leaf that our improvements are shown to be applied, and which 85 are described as follows. The leaf is formed with a horizontal groove, R, extending entirely across its rear face, of dove tailed cross section having the greater width at the bottom, or with the bevel of its sides overhanging the groove. At the central part of the leaf is a space, t, the depth of which is substantially coincident with the width of the groove. In the groove are fitted a pair of thin blades which are together adapted to 90 form the sight notch, and which may be variously constructed or modified for different purposes, conditions or effects. In the modification shown in Figs. 1 and 2 the blades, n, are seated in the same plane at the respective 100 ends of the groove, R, overlapping upon the space, t, and nearly abutting in the central vertical plane of the sight to provide an attenuated slot, e¹, or line of light in downward continuation of the bottom or point of the 105 sighting notch, e², formed by the inclined configuration of the upper inner end portions of the blades, as shown. This arrangement

of the blades forms the subject of a separate application, and therefore will here require no further description, but the construction forming the subject of this application is shown in the remaining figures, the description of which is as follows, referring particularly to Figs. 3 to 11 inclusive.

The blades, n^1 , n^2 , are fitted in the groove, R, of the leaf, one back of the other, that is 10 in two separate planes side by side, the front blade, n^1 , being slightly wider than the rear blade, n^2 , owing to the greater width of the bottom of the groove due to its dovetailed form. In length the blades are shorter than 15 the groove or leaf, being about three fourths the length of the groove as proportioned in the drawings and both are made of very thin stock. Each blade has a rhomboidal notch, n^3 , near one end, at its upper edge, having 20 the side nearest the adjacent end of the blade forming an obtuse angle with the lower side of the notch, and the opposite side forming an acute angle therewith. Said notches are placed respectively near opposite ends of the 25 blades, or in other words are of right and left handed construction so that the sides of the notches of the respective blades are of reversed inclination relatively to each other when in position in the groove of the leaf. 30 In the upper edges of the opposite ends of the blades are the semicircular notches, n^4 , n^5 , of differential proportions, the notch, n^5 , in the rear blade, n^2 , being much smaller than that of the front blade, n^4 , for obtaining different 35 effects in sighting.

The blades are secured in the groove, R, by means of binding screws, i^1 , screwed into screw threaded perforations, i^2 , in the leaf on the lower side of the groove, in such position 40 that the heads of the screws will impinge slightly upon the lower edges of the rear blade, n^2 , to clamp the blades in their seats. Suitable countersinks, i^3 , are formed around the perforations, i^2 , to receive the 45 heads of the screws and permit the latter to be screwed down below the surface of the leaf to the extent necessary to insure contact with the blades when the latter are in any degree below said surface of the leaf.

50 In operation, the above described construction of the blades provides four different styles of sighting notch by means of different positions or relation of the blades to each other in the groove, R. These several combinations of the blades and their resultant notches are shown in the Figs. 4 to 7 inclusive, and are as follows. If the ends of the blades farthest from the rhomboidal notches be drawn out flush with the ends of 55 the leaf, as shown in Fig. 7, then those sides of the notches which form obtuse angles with the bottom thereof will together form a triangular notch, r^1 , for the said side of the notch of the front blade, n^1 , will be visible to 60 the eye, through the notch of the rear blade. 65

By pushing the blades a short distance in toward the central plane of the leaf, the opposite sides of the rhomboidal notches will be brought into juxtaposition as shown in Fig. 6, thus producing a "caliper" form of 70 notch, r^2 . With both blades arranged with their ends flush with that end of the leaf which will bring the rhomboidal notch of the rear blade central of the leaf, the semicircular notch, n^4 , of the front blade, n^1 , will be 75 brought into sighting position, as shown in Fig. 5, while with the blades arranged with their opposite ends flush with the opposite end of the leaf the notch, n^5 , of the rear blade, n^2 , will be brought into sighting position unobstructed by the front blade, the rhomboidal notch of which will also then be 80 central of the leaf, as shown in Fig. 4.

Figs. 12 and 13 correspond to Figs. 7 and 6, but show blades, n^{11} , n^{12} , in which the 85 notches instead of being of rhomboidal form, have one side inclined, and the other of the form of a step, as shown, which produces the triangular notch, r^1 , of Fig. 7, and the true "caliper" notch, r^3 , as shown in Fig. 13. 90 Various other forms of sighting notch may be obtained, here requiring neither to be shown or described.

The sight leaf, H, is adapted to be folded forward and down to the horizontal position 95 to permit the use of the secondary sight leaf, L, which may then be raised to place. The leaf, L, folds correspondingly down and rearward while the main leaf is elevated, as shown in the drawings. But these features 100 are wholly independent of our invention, which relates to the combination of the grooved leaf and the blades forming the sighting notches of differential configurations. This construction is equally applicable to both folding and non-folding sight leaves or those of any other class. 105

We claim as our invention.

1. In sights for firearms the combination of a pair of leaves or blades provided with 110 notches of identical form having sides of differential shape, whereby the blades when overlaid upon each other with their notches reversed respectively form the opposite sides of two separate forms of sighting notch. 115

2. In a sight for firearms the combination of a leaf, and a pair of blades provided with notches of identical form having sides of differential shape secured to the leaf, one overlaid upon the other with the notches relatively reversed and respectively forming the opposite sides of the sighting notch. 120

3. In sights for firearms, the combination of a suitable supporting element provided with a groove, a pair of blades slidably mounted in said groove and provided in their respective edges with notches of identical form having sides of differential shape, said parts being shiftable relative to each other to place their respective notches in 125 130

different positions to provide different forms of sighting notch.

4. In a sight for firearms, the combination of a suitable supporting element, a plurality of coöperating sight-forming members, each of which has a plurality of sight elements, said members being movably mounted on said supporting element so that they may be moved with reference to the said element 10 and with reference to each other to produce sighting notches of different form.

Signed by us at Middlefield, Connecticut, this 28th day of December 1906.

JAMES WINDRIDGE.
GEORGE S. WILCOX.
